UNITED STATES PATENT OFFICE.

HENRY A. CARPENTER AND ARTHUR W. WARNER, OF SEWICKLEY, PENNSYLVANIA,
ASSIGNORS TO RITER-CONLEY MANUFACTURING COMPANY, OF PITTSBURGH, PENN-
SYLVANIA, A CORPORATION OF NEW JERSEY.

TELESCOPING-CHUTE STRUCTURE.

1,229,224.

Specification of Letters Patent. Patented June 12, 1917.

Application filed September 16, 1914. Serial No. 862,031.

To all whom it may concern:

Be it known that we, HENRY A. CARPENTER and ARTHUR W. WARNER, citizens of the United States, residing at Sewickley, in the county of Allegheny and State of Pennsylvania, have invented certain new and useful Improvements in Telescoping-Chute Structures, of which the following is a specification.

10 This invention relates to improvements in telescoping chute structures particularly adapted for use in connection with the charging and discharging apparatus for gas retorts, the structures being adapted to form 15 a passageway for the coal which is to be charged to the retorts.

Charging and discharging apparatus shown in United States Patents #1,171,398 of February 8, 1916, and #1,171,414 of 20 February 15, 1916, employ a hopper containing coal to be charged, a horizontally movable charger, and a telescopic conduit for delivering a charge of coal to the charger at suitable time intervals. The first 25 patent mentioned also shows means for effectively preventing the escape of dust during the passage of the fine coal from the supply to the charger.

In the telescopic chute construction shown. 30 in Patent #1,171,398 above referred to, the inner section of the chute is fixedly positioned as to height and the remaining sections movable relatively thereto in a vertical direction while retaining the joints between the sections and frame substantially 35 dust proof.

In operation of structures of this character it has been found desirable to provide means for permitting an adjustment of the 40 inner section supporting means under normal operating conditions as well as a vertical movement of said means under abnormal conditions, and the present invention has among its objects means for accomplishing these ends while maintaining the advantages present in the patented structure mentioned. In the construction shown herein 45 we provide means for supporting the chute

with its opposite ends independently supported under normal conditions and with a 50 common support under abnormal conditions.

In the accompanying drawings, in which similar reference characters indicate similar parts in each of the views,

Figure 1 is a vertical cross-sectional view 55 of a telescopic conduit and its supporting means constructed in accordance with the present invention, the parts being shown in telescoped position;

Fig. 2 is a horizontal sectional view taken 60 on the line 2—2 of Fig. 1;

Fig. 3 is a side elevation of the telescope structure shown as secured to a beam carried by a charging machine; and

Fig. 4 is a detail sectional view showing 65 the manner in which the dust-proof joint is formed when sections are extended.

In the accompanying drawings, 10 designates a plurality of sections adapted to telescope, these sections being of suitable configuration in horizontal section, this configuration in the use heretofore referred to being preferably rectangular. These sections are generally of similar form but of different area on such horizontal section, having 70 75 their upper ends bent outwardly to form flanges 11, these flanges being of a lateral width greater than the distance between adjacent sections. Each flange 11 is also provided with a member 12 which is of a width 80 greater than the width of the flange and preferably projects both inwardly and outwardly beyond the flange as shown in Fig. 1; these members being positioned on the top face of the flange. 85

Externally of the bottom of each section is provided a strip member 13, this member extending into the space between two sections, and forming both a stop member to limit the extending movements of the next 90 outer section by contact therewith of the member 12 of said next section, these two members also acting to form the joint when the relative movements of the two sections place them in extended relationship. When 95 the sections are in telescoped position, the

members 12 contact with the end faces of the flanges 11 and thus provide the closed joint between such sections.

- However, the inner section 10^a and the outer section 10^b differ somewhat from the general section structure, the flange 11 being omitted with respect to the section 10^a and the strip member 13 omitted in connection with section 10^b.
- 10 The section 10^a, instead of being supported by the remaining sections, is secured to the downwardly projecting portion of a frame 14 which loosely surrounds a stationary conduit 15 projecting downwardly from the hopper (not shown). The strips 12^a for the first movable inner section serve the functions of the strip 12 for the said section by contact with the horizontal portion of the member 14.
- 20 The supporting members 14 are carried by a plurality of threaded rods or bolts 16, said rods or bolts being secured to the member 14 and adapted to extend upwardly through openings in an outwardly flanged portion 17 of the stationary frame, said rods or bolts being freely movable through said opening and carrying above the flanged portion 17 suitable supporting devices such as nuts 18 which act in the nature of seats. The outer section 10^b is secured to angle bars 19, these bars being secured to channels 20 carried by girder 21 of the charging machine, said girder being adapted to travel vertically by the action of the hoisting mechanism of the machine, represented in Fig. 3 by the threaded member 22, the rotation of the latter acting to move the girder 21 in a vertical direction. Since the girder and the charger are relatively positioned to have their vertical movements in correspondence, it will be understood that any vertical movement of the charger will provide a corresponding movement to the channels 20 and to the outer section 10^b and retain the lower end of the chute 40 in permanent position with respect to the charger, but movable with respect to the hopper. The lower end of the outer section is preferably contracted inwardly below the lower ends of the remaining sections 10, thus 45 forming a passageway through the inner member 10^a leading toward the charger (not shown). Said contracted lower end is supported by a suitable casing 23 secured to a frame work member 23^a of the charger.
- 50 As will be seen in Fig. 1, in which the sections are shown as telescoped, all of the intermediate sections are supported by the outer section 10^b by reason of the superposed contact of the flanges 11 and members 12, the 55 contact thus formed causing the member 12^a to contact with the member 14. This is the relative positions of the parts when the charger is in the zone of safety for the upper

row of retorts. Should the operator, in moving the hoisting mechanism, cause the charger 65 to move upwardly beyond a predetermined point, the contact engagement of the pack would simply cause the member 14 to be raised a small distance and thus place the weight of the inner section and the member 70 14 on the pack instead of on the nuts 18, the rods or bolts 16 passing upwardly during such movement. Obviously, a downward movement of the charger permits the pack to move downwardly, and when contact is 75 made between the nuts 18 and the flange 17, the weight of the inner section and of the member 14 will be transferred from the pack to the flange 17. If the downward movement of the charger is sufficient to bring it 80 within the next zone of safety, the travel of the girder 21 will have been sufficient to cause the pack (with the exception of the section 10^a) to move downwardly a distance 85 which will place the member 12^a in contact with the strip member 13 of the section 10^a, this being the position shown in Fig. 4 of the drawings, and in which the joint between the member 10^a and the next outer member is closed between the member 12^a and the strip 90 member 13 of section 10^a. Similarly, a further downward movement of the charger to the succeeding zone of safety causes the next inner section to contact with the strip 13 of the section previously extended, thus placing the 95 weight of the previously extended section on the flanged portion 17 instead of the charger member 19, this divided support being the normal condition of the conduit and changed only when the upward movement has reached 100 the point where the nuts 18 are carried out of contact with the flanged portion 17 whereupon the entire support is placed on the angle members 19. As this latter takes place only in connection with the upper row of 105 retorts it may be considered somewhat as an abnormal condition.

Obviously, this movement of the member 14 under abnormal condition would be relative to the member 15 and to permit of a 110 ready movement of the parts without destroying the dust-retaining joint structure we preferably employ a felt packing 24 interposed between the member 14 and a plate 25 secured in spaced relation thereto, the felt 115 packing being preferably held in contact with the member 15 by means of springs or other suitable devices 26. While this arrangement provides for a wipe joint structure, the movements of the member 14 are 120 only under such abnormal conditions and relatively small, so that the general objection to wipe joints in connection with devices of this type becomes immaterial.

As will be readily understood, by arranging the rods or bolts 16 as threaded mem-

- bers, the points of contact of members 12 with members 13 can be adjusted, such adjustment providing the proper location for the inner section 10^a, and the remaining sections providing their contacts at the proper points in connection with succeeding horizontal rows of retorts, it being understood that the length of travel of each section between a point where its member 12 contacts 10 with the superposed flange 11 of the adjacent section and the point where it contacts with the member 13 of that section corresponds to the distance between the centers of adjacent retorts.
- 15 What we claim is:
1. In combination, a telescopic sectional chute, a supply member entered therein, means for supporting the chute with its opposite ends independently supported under 20 normal conditions and with a common support under abnormal conditions, said means including an end-section support surrounding the supply member and movable independently thereof and relatively thereto 25 under abnormal conditions.
  2. In combination, a telescopic sectional chute, a supply member entered therein, means for supporting the chute with its opposite ends independently supported under 30 normal conditions and with a common support under abnormal conditions, said means including an end-section support surrounding the supply member and movable independently thereof and relatively thereto 35 under abnormal conditions, and means for adjusting the end-section support relatively to the supply member.
  3. In combination, a fixed supply member, a telescoping sectional chute, and means for 40 supporting the chute with its opposite ends independently supported under normal conditions and with a common support under abnormal conditions, said means including a fixed support, an end-section support 45 rounding the supply member, and means interposed between said last mentioned supports, comprising rods carried by the end-section support and projecting through and supported by the fixed support, said end-section support being movable relatively to the supply member under abnormal conditions.
  4. In combination, a supply member, a sectional telescopic chute external of said 55 member and forming an extension of the passageway through the member, a chute support external of said member and adjustable lengthwise thereof, and joint closing means carried by the telescoping sections.
  5. In combination, a supply member, a telescoping sectional chute external of said 60 member, means for supporting the chute with its opposite ends independently sup-
- ported under normal conditions and with a common support under abnormal conditions, 65 said means including an end-section support movable relative to the supply member under such abnormal conditions, and dust-proofing packing structures movable with such end-section support. 70
6. In combination, a supply member, a telescoping sectional chute external of said member, independent supporting members for the opposite ends of the chute, one of said supporting members being normally 75 fixedly positioned relative to said supply member, and means for variably adjusting such normal position.
  7. In combination, a supply member, a telescoping sectional chute external of said 80 member, independent supporting members for the opposite ends of the chute, one of said supporting members being normally fixedly positioned relative to said supply member, and means for variably adjusting 85 such normal position, said latter means including a fixed support, threaded rods carried by said supporting member and supported on the fixed support, said rods carrying seats adjustable thereon. 90
  8. In combination, a supply member, a chute external of said member and forming an extension of the passageway through the member, a chute support external of said member and adjustable lengthwise thereof, 95 and packing for closing the joint between the member and support.
  9. In combination, a supply member, a chute external of said member and forming an extension of the passageway through the 100 member, a chute support external of said member and adjustable lengthwise thereof, and packing for closing the joint between the member and support, said packing being carried by and movable with the support. 105
  10. In combination, a supply member, a chute external of said member and forming an extension of the passageway through the member, a chute support external of said member and adjustable lengthwise thereof, 110 and packing for closing the joint between the member and support, said support carrying a plate member adapted to form a packing receiving recess.
  11. In combination, a supply member, a 115 chute external of said member and forming an extension of the passageway through the member, a chute support external of said member and adjustable lengthwise thereof, and packing for closing the joint between the member and support, said support carrying a plate member adapted to form a packing receiving recess, said recess carrying the yieldable means for retaining the packing in contact with said member. 120
  12. In combination, a supply member, a

chute external of said member and forming an extension of the passageway through the member, a chute support external of said member and adjustable lengthwise thereof, and packing for closing the joint between the member and support, a fixed support above said adjustable support, and means extending between said supports normally coöperating with the fixed support to position the adjustable support, said means be-

ing freely movable in one direction relative to the fixed support under abnormal conditions.

In testimony whereof we affix our signatures in presence of two witnesses.

HENRY A. CARPENTER.
ARTHUR W. WARNER.
